UNITED STATES PATENT OFFICE.

JESSIE JANES, OF BELLEVUE, KENTUCKY, ASSIGNOR OF ONE-HALF TO CHARLES R. HALL, OF CINCINNATI, OHIO.

DUST-COLLECTOR.

1,228,561.

Specification of Letters Patent.

Patented June 5, 1917.

Application filed January 13, 1917. Serial No. 142,122.

To all whom it may concern:

Be it known that I, JESSIE JANES, a citizen of the United States of America, and resident of Bellevue, in the county of Campbell and State of Kentucky, have invented 5 a new and useful Improvement in Dust-Collectors, of which the following is a specification.

An object of my invention is to produce 10 a dust collector for hot air furnace pipes, which is capable of being cleaned repeatedly without impairing the effectiveness thereof and which may be placed in position and used within the pipes without diminishing 15 the supply of air passing therethrough.

This and other objects are attained in the construction described in the following specification and illustrated in the accompanying drawings, in which:

20 Figure 1 is a plan view of a dust collector embodying my invention, in position in a hot air furnace pipe.

Fig. 2 is a sectional view of the furnace pipe with my improved dust collector 25 mounted therein, taken on the line 2—2 of Fig. 1.

Fig. 3 is a sectional view of the furnace pipe and my improved dust collector, taken 30 on the line 3—3 of Fig. 1.

Fig. 4 is a plan view of a modified form 35 of dust collector embodying my invention, mounted in a furnace pipe.

Fig. 5 is a sectional view of the construction disclosed in Fig. 4 and taken on the 40 line 5—5 thereof.

My improved dust collector consists of a frame 6 of sheet metal, having a series of vanes 7 located therein and secured in the sides thereof by having their ends passing 45 through slots 8 in the frame and provided with lugs 9 adapted to be bent into engagement with the sides of the frame, the slots being inclined to hold the vanes in the inclined positions shown. At each end of the 50 frame, hooks 10 and 11 are provided, these hooks being adapted to engage the top edges of the ends of the sheet metal housing 12 provided for the register 13 located in the floor 14, the housing communicating with the usual hot air pipe 15. The inner surfaces of the frame and both surfaces of each 55 of the vanes are coated with fire proof cement which, while still in its adhesive condition, permits of the attachment thereto of a coating of fluffy asbestos 21. The coat-

ing of asbestos is sufficient substantially to close the spaces between the frame and vanes and between adjacent vanes, to prevent the passage of air therethrough without having to be brought into contact with the asbestos. Carded asbestos is employed for this purpose so as to afford a sufficiently porous mass to allow the air to pass through it freely and yet having a sufficient number of minute flakes to prevent the passage of dust 65 through the collector.

The construction disclosed in Figs. 4 and 5 is adapted to be used in round pipes or to be located in the pipes immediately below the housing 12 in which the register is 70 located, as disclosed. This modified form consists of a circular frame 16 of sheet metal having its upper edge turned over to form a series of supporting lugs 17 adapted to rest on the bottom 18 of the housing 12 in 75 which the register 13 is located, these lugs supporting the collector within the pipe. Extending across the frame 16 and secured therein in the same manner that vanes 7 are secured in frame 6 of the construction disclosed in Figs. 1 to 3 inclusive, are a series 80 of vanes 19, which are located in vertical, horizontal, and inclined positions. By thus staggering and positioning the vanes, the air passing through the pipe is baffled and 85 caused to be projected against the asbestos 20 attached thereto, in much the same manner that the air impinges the asbestos 21 of the construction previously described. In addition to cementing the asbestos to the 90 vanes 19, I also coat the interior of the frame 16 therewith to aid in the collection of dust passing through the pipe.

My improved dust collector is placed within the pipes in the position shown, and used 95 until the dust collected thereby has impregnated the fibers of the asbestos to such an extent as to completely fill the interstices thereof. Then the collector is lifted from its position within the pipe and is carried 100 to an open flame. The flame is then allowed to pass through the asbestos and to consume all of the dust collected thereby. This completely cleanses the collector, the ashes, should any remain, being easily removed by 105 shaking the frame slightly.

My improved construction is one particularly adapted to be sterilized by the passage therethrough of a flame, in that the heat necessary to cleanse the collector will 110

not detrimentally affect its construction by weakening or warping it. In other constructions heretofore employed, the use of heat as a cleansing agent is not possible since they are too delicate for such a treatment and can only stand the action of such cleansing agencies as air and water. In the use of water in connection with dust collectors having such delicate constructions and employing thread-like collecting material therein, 10 the tendency of the water is to mat the material and to render it ineffective for the purpose for which it was provided.

Having thus described my invention, what 15 I claim is:

1. A dust collector consisting of a sheet metal frame, a series of parallel metal vanes located therein and spaced therefrom and from each other, and a coating of dust oc- 20 cluding fire proof material attached to both sides of the vanes and to the inside of the frame, said vanes being inclined at angles

to the direction of the normal passage of air through the collector.

2. A dust collector comprising a sheet 25 metal frame adapted to be located within an air pipe, a series of sheet metal vanes located therein spaced therefrom and from each other and adapted to baffle the air passing through the pipe, and carded asbestos 30 attached to the vanes and to the interior of the frame and extending into the spaces between the vanes and the frame, said vanes being inclined at angles to the direction of the normal passage of air through the col- 35 lector.

In testimony whereof, I have hereunto subscribed my name this 11th day of January, 1917.

JESSIE JANES.
